CLAIM

The ornamental design for an orthosis, as shown and described.

DESCRIPTION

FIG. 1 is a front perspective view of a first embodiment of an orthosis showing my new design;

FIG. 2 is a rear view thereof;

FIG. 3 is a front view thereof;

FIG. 4 is a left side view thereof;

FIG. 5 is a right side view thereof;

FIG. 6 is a front perspective view of a second embodiment showing my new design;

FIG. 7 is a rear view thereof;

FIG. 8 is a front view thereof;

FIG. 9 is a left side view thereof; and,

FIG. 10 is a right side view thereof.

The broken lines shown in the drawings depict environment and form no part of the claimed design.

1 Claim, 10 Drawing Sheets
